CLAIM

I claim the ornamental design for a photoelectric switch, as shown and described.

DESCRIPTION

FIG. 1 is a front view of a photoelectric switch showing my new design, the rear view being a mirror image thereof;
FIG. 2 is a right side view of the same photoelectric switch, a left side view being identical to the right side view;
FIG. 3 is a top plan view of the same photoelectric switch;
FIG. 4 is a bottom view of the same photoelectric switch;
FIG. 5 is a sectional view of the same photoelectric switch taken along 5—5 lines in FIG. 1;
FIG. 6 is a sectional view of the same photoelectric switch taken along 6—6 lines in FIG. 1;
FIG. 7 is a sectional view of the same photoelectric switch taken along 7—7 lines in FIG. 3; and,
FIG. 8 is a perspective view of the same photoelectric switch.
